UNITED STATES PATENT OFFICE

2,668,623

FILTERING APPARATUS

David J. Munroe, Racine, Wis., assignor to Webster Electric Company, Racine, Wis., a corporation of Delaware

Application April 6, 1950, Serial No. 154,390

3 Claims. (Cl. 210—152)

1

The present invention relates to apparatus for filtering or straining fluids and has for one of its primary objects the provision of new and improved apparatus which can be made economically, is durable and efficient in operation, and can be readily combined as a unitary structure with an associated pump.

One of the objects of the present invention is the provision of a new and improved filtering apparatus including a rotary cleaner element of novel construction.

A further object of the present invention is the provision of a new and improved filtering apparatus including a cleaner blade assembly comprising a polygonal blade element, the corner portions of which extend into a filter slot and which may be supported by a pair of blade supporting discs secured to the opposite sides of said blade.

A further object of the present invention is to provide a new and improved rotary filter including a rotatable self-aligning cleaner blade assembly.

A further object of the present invention is the provision of a new and improved combined fluid pump and rotary filter constructed and arranged so that the filter can be readily driven by the pump shaft and adds but little to the inertia of the rotating parts of the apparatus and the load imposed upon the driving motor.

A still further object of the present invention is the provision of a new and improved combined fluid pump and strainer wherein a filtering slot is provided by a portion of the pump cover plate and includes a complementary cleaner cover plate, the two plates being so constructed and arranged that they are held in assembled relation relative to the remainder of the pump by the same securing means.

In brief, the filter of the present invention includes a structure defining a narrow annular filtering slot, which structure may include a pair of opposed, slightly spaced apart, annular filter walls on a pump cover plate and a cleaner cover plate. A rotatable cleaner blade assembly is mounted between the plates. The assembly includes a cleaner blade having a portion extending into the slot. The blade is preferably of polygonal construction and has its corner portions extending into the slot. The blade is relatively thin and is supported by discs secured to the opposite sides of the blade. The blade and discs are provided with a central shaft receiving aperture into which extend opposed radial tongues fitting into a diametrical slot on the end of the shaft, whereby the assembly is drivingly associated with the shaft. The tongue and slot connection is such to permit relative axial movement between the shaft and assembly whereby the assembly is floating or self-aligning in construction.

2

Other objects and advantages of the present invention will become apparent from the ensuing description of an illustrative embodiment thereof, in the course of which reference is had to the accompanying drawings, in which

Fig. 1 is a side elevational view, partially in section, of a combined pump and filter constructed in accordance with the present invention;

Fig. 2 is a cross sectional view taken along the line 2—2 of Fig. 1;

Fig. 3 is an end elevational view, also partly broken away, of the apparatus;

Fig. 4 is an exploded view illustrating details of the filter; and

Fig. 5 is an enlarged fragmentary cross sectional view through the filter slot and illustrating the cleaning action of the rotary filter blade.

Referring now to the drawings and first to Figs. 1 and 3, the present invention has been illustrated in conjunction with what is commonly known as a fuel unit. This unit comprises a liquid (fuel oil) pump, a pressure regulator, and the rotary filter of the present invention. The invention may be used, though, with other apparatus, such for instance as with lubricating equipment.

The fuel unit, as a whole, is indicated by the reference character 10. It comprises a housing portion 12 within which is mounted most of the pump and including a portion 14 within which is mounted the pressure regulator. The latter has not been illustrated in detail inasmuch as it may take various forms. The pump may also be of conventional construction except as it may be modified as hereinafter described in order to associate the filter therewith. A portion only of the pump has been illustrated, this portion including a gear plate 16, within which are mounted the component parts of a gear pump such as the gears 18 and 20, and a gear cover plate 22. The housing is completed by an end portion 24 defining at its interior a liquid inlet chamber 26 communicating with a suitable source of supply of liquid through an inlet passageway 28 having a flow restricting orifice 30 therein. The pump gears are driven by a motor driven shaft 32 which projects through the gear cover plate into chamber 26. The pump includes also a pump discharge passageway 34, see Fig. 3, leading to the pressure regulator valve and a pump inlet passageway 36 partly in the gear plate and partly in the gear cover plate, as indicated by reference character 38 in Figs. 1 and 4.

The fluid filtering apparatus of the present invention includes structure defining one or more filter slots, only one being shown, this structure including a pair of annular filter walls 40 and 42 in the gear cover plate 22 and a filter cover plate 44, respectively. The wall 42 extends axially outward from the gear cover plate 22, while the

wall 42 extends inwardly from the cover plate 44. Proper spacing between the two cover plates and filter walls may be obtained in a suitable manner. As illustrated, this is readily and simply accomplished by axially projecting bosses 46 on the gear cover plate, opposed bosses 48 on the radially outwardly extending fingers 50 on the gear cover plate, and the spacer shims 52. The arrangement is such as to provide a narrow annular filter slot which is indicated by the reference character 54, the width of which is readily determined by the thickness of the shims 52. The various parts including the two cover plates and shims are held in assembled relation by the screw bolts 56, customarily used in holding the gear cover plate in place. As noted above, more than one slot could be used if a higher capacity is required.

The filter includes also a cleaner blade assembly, indicated as a whole by reference character 60, and mounted in the recess 62 between the cover plates. The cleaner blade assembly for a single slot construction such as that illustrated and described, includes a polygonal, preferably square, cleaner blade 64, the corner portions of which extend into the filter slot as well as beyond the peripheries of the annular discs 66 secured to the opposite sides of the blade and supporting it. The discs and blade can be held in assembled relation in suitable manner as by the rivets 68. The cleaner blade is preferably quite thin, having a thickness of about .004 inch, and for this blade the slot should have a width of about .005 inch to .006 inch so that the blade thickness is essentially equal to the slot width.

The cleaner blade assembly is drivingly connected with the pump shaft 32 in such manner as to permit the blade assembly automatically to align itself in the cleaner slot. This is accomplished by a tongue and slot connection including a central aperture 70 in the assembly, the radially inwardly extending tongues 72 on the assembly, and a diametrical slot 74 at the end of the shaft. Instead of a diametrical slot oppositely located keyways could be formed on the shaft or the shaft could be square or of other configuration, such as D-shaped and the assembly have a corresponding opening. The driving connection is effective, yet enables the shaft and assembly to have some relative movement, thereby to make the blade substantially self-aligning to compensate for variations in length of shaft, etc. In the case of the multiple slot construction mentioned above a number of the assemblies can be placed axially of the shaft so as to be individually self-aligning relative to their respective slots.

The filter unit of the present invention, which may be noted from the foregoing detailed description, can be constructed economically and simply. It can be assembled readily relative to the filter slot defining structure and the latter can readily be constructed as a unit with a pump, this requiring but a slight change in the construction of the gear plate cover.

Filtering of the oil flowing into the inlet chamber 26 through the inlet 28 is accomplished when the fluid flows through the filter slot 54 effectively in the area between the corners of the cleaner blade. The slot is kept clean effectively by the cleaner blades, which are particularly effective because of the fact that the corners project into the slot, thereby to provide an effective cutting and throwing out action upon foreign particles or sludge 76, as shown in Fig. 5.

The filter of the present invention is not only advantageous from the standpoint of simplicity and economy of manufacture and effectiveness of operation, but it also minimizes the number of rotary seals which may be required. In the instant case merely a good running fit between the shaft 32 and the gear cover plate 22 is required. It is also light so as to add but little load upon the pump driving motor.

While the present invention has been described in connection with details of an illustrative embodiment, it should be understood that these details are not intended to be limitative of the invention, except insofar as set forth in the accompanying claims.

Having thus described my invention, what I desire to claim as new and desire to secure by Letters Patent of the United States is:

1. A rotatable filter assembly comprising a thin square cleaner blade and circular supporting discs secured to opposite sides of said blade, said discs being dimensioned to leave exposed only the corner portions of said blade, and said discs and blades being centrally apertured for driving cooperation with driving means.

2. A combined liquid pump and filter unit, including in combination, a pump gear cover plate having an axially outwardly projecting annular straining wall and a pump inlet passageway extending through said plate and the inlet end of which is located radially inwardly of said wall, a filter unit cover plate located adjacent said pump cover plate and having an annular strainer wall in axial alignment with and projecting axially toward said first wall, securing means disposed radially outwardly of said walls for supporting said plates in fixed spaced relationship with adjacent ends of said walls being spaced apart a slight distance, thereby to define a central cavity communicating with said inlet passageway and a narrow annular planar filter slot communicating with said cavity, a rotatable pump shaft having a portion extending through said gear cover plate into said cavity, a cleaner plate assembly mounted on said shaft in said cavity and including a cleaner plate having a portion extending into and rotatable in said filter slot, a housing surrounding said plates and defining a liquid inlet chamber, and means for supplying liquid to said inlet chamber whereby liquid flows through said annular slot into said cavity and thence into said pump inlet passageway.

3. A combined liquid pump and filter unit as claimed in claim 2, wherein said securing means disposed radially outwardly of said walls includes angularly spaced apart radially outwardly extending structures on said filter cover plate, said structures and gear cover plate having aligned apertures, apertured spacer shims located between said plates with these apertures in alignment with said first mentioned apertures, and common securing bolts passing through said cover plates and shims.

DAVID J. MUNROE.
